SINGLE AND MULTIPLE BEND TANGENT
BENDING MACHINE

Lee B. Green, Lakewood, Ohio

Application February 28, 1950, Serial No. 146,903

13 Claims. (Cl. 153—46)

1

This invention relates to bending machines of the kind in which a bending die is tangentially rockable, as by means of a swinging wing, around an anvil die member for bending a metal workpiece to a desired shape.

Bending machines of this kind have come to be known in the trade as "tangent benders" and are very practical and useful for producing smooth bends in various articles of manufacture, such as housings for round-top refrigerator cabinets, metal shells and containers of various shapes, and numerous other products. These tangent benders are especially useful for producing articles of this character from longitudinally flanged sheet metal workpieces by bending the web portion of the workpiece out of its own plane and simultaneously bending the flange or flanges of the workpiece within their own planes. Such bending of the flanges within their own planes is carried out substantially without wrinkling or buckling and without need for previously notching the flanges.

In the tangent benders heretofore provided, so-called "radius gears" were employed to insure the attainment of a true rocking movement between the bending die and the anvil die and to eliminate relative slipping therebetween which was undesirable because of scoring and other harmful effects produced on the workpiece. The tangent benders embodying such radius gears were subject to the disadvantage that when an anvil die of a different curvature was substituted in the machine for the production of workpieces having such a different curvature, it was also necessary to substitute other radius gears in the machine if the above-mentioned objectionable slipping between the bending die and anvil die were to be prevented. To provide a number of such radius gears of various curvatures represented substantial equipment expense and the work of substituting the radius gears in the machine caused delays in production and resulted in expensive labor costs.

The present invention eliminates this disadvantage and, as one important object, provides an improved construction for such a tangent bender in which the travel of the bending die around the anvil die is controlled or modified so as to constitute a true rocking movement substantially free of objectionable slippage.

Another important object of this invention is to provide an improved construction for a tangent bending machine of the character indicated, which is readily adaptable to the production of bends of various different shapes and

2

radii by the substitution of anvil die members of the desired shapes or curvatures therein and in which novel means is employed for controlling or modifying the movement of the bending die to adapt the same to the shape or radius of the particular anvil die member being used in the machine, such that the bending die will always have a true tangential rocking movement which is substantially free of objectionable slipping.

10 Another object is to provide an improved construction for such a tangent bender in which the bending die is mounted on a carrier so as to be capable of translatory movement relative to the actuating wing and in which means effective on the carrier imparts such translatory movement thereto during the swinging of the wing for causing the bending die to have the desired true tangential rocking movement on the anvil die member.

20 A further object is to provide an improved construction for a tangent bender of the character mentioned, in which the means for imparting the translatory movement to the bending die is in the form of a reaction thrust mechanism responsive to relative movement between the wing and frame.

25 Still another object is to provide an improved tangent bender in which the mechanism for imparting the translatory movement to the bending die includes a rock shaft mounted on the wing and a thrust transmitting means forming an operative connection between the rock shaft and the bending die.

30 Yet another object is to provide an improved construction for a tangent bender in which the reaction thrust mechanism includes linkage pivotally anchored on the frame by an anchor pivot means which is adjustable to different values of eccentricity relative to the pivot axis of the wing, and by which the translatory movement to be imparted to the bending die can be varied as desired and to best suit the shape or radius of curvature of the particular anvil die member being used in the machine.

35 As another of its objects this invention provides an improved construction for a tangent bender in which a tangent bending head is mounted on a base having a work clamping means thereon and is movable on said base for adjustment relative to said clamping means for determining the location at which the bend is to be formed in the workpiece.

40 Another object is to provide an improved construction for a tangent bending machine in which

a pair of tangent bending heads are mounted on a base on opposite sides of a work clamping means and are movable on such base for adjustment relative to the clamping means for determining the locations at which the bends are to be formed in the workpiece.

It is also an object of this invention to provide an improved tangent bender in which a pair of cooperating clamping dies are carried by movable and stationary frame portions so as to define a gap into which the workpiece can be inserted from the front of the machine and in which an upright frame portion at the rear of the machine provides a support for fluid cylinder power devices for actuating the clamping and bending dies.

The invention can be further briefly summarized as consisting of certain novel combinations and arrangements of parts hereinafter described and particularly set out in the claims hereof.

In the accompanying sheets of drawings:

Fig. 1 is a side elevation of a bending machine embodying the present invention;

Fig. 2 is a top plan view of the machine;

Fig. 3 is a front elevation of the machine;

Fig. 4 is a partial rear elevation showing one of the overhanging portions located at the rear of the machine, the view being taken approximately as indicated by line 4-4 of Fig. 2;

Fig. 5 is a partial elevation of the same overhanging portion of the machine, the view being taken approximately as indicated by line 5-5 of Figs. 2 and 4;

Fig. 6 is a partial vertical section taken through the machine from front to back thereof and at a point adjacent the work clamping means, as indicated by section line 6-6 of Fig. 2;

Fig. 7 is a partial vertical section taken through the machine transversely thereof, as indicated by line 7-7 of Fig. 2;

Fig. 8 is a fragmentary vertical section taken through one of the tangent bending heads, as indicated by section line 8-8 of Fig. 1, and showing the wing and bending die in their initial position;

Fig. 9 is another fragmentary vertical section taken through one of the tangent bending dies, as indicated by section line 9-9 of Fig. 1, and showing the position of the wing and bending die at the completion of a radius bend;

Fig. 10 is a fragmentary sectional view taken through the thrust reaction linkage, as indicated by line 10-10 of Fig. 3;

Fig. 11 is a fragmentary sectional view taken through a wing pivot and the anchor bracket for the thrust reaction linkage, as indicated by section line 11-11 of Fig. 3;

Fig. 12 is a fragmentary perspective view further illustrating a latch device of the improved machine;

Fig. 13 is a fragmentary vertical section similar to Fig. 9, but showing the position of the wing and bending die at the completion of a right-angle bend;

Fig. 14 is a side elevation of a flanged sheet metal workpiece;

Figs. 15 to 18 inclusive, are diagrammatic views showing the progressive forming steps performed on the workpiece of Fig. 14 in producing a desired product therefrom by a bending machine having a single tangent bending head; and

Figs. 19 and 20 are similar diagrammatic views showing the progressive forming steps performed on the workpiece of Fig. 14 in producing

a desired product therefrom by a bending machine having a pair of tangent bending heads.

The drawings show the improved bending machine 10 as comprising a base 11 having workholding means 12 mounted thereon at an intermediate point and a pair of tangent bending heads 13, 14 mounted on said frame on opposite sides of the workholding means. Figs. 1, 3, 5 and 7 of the drawings also show a workpiece 15 in the machine and on which the bending operations are being performed. Before proceeding with the detailed description of the improved machine 10, it should be explained that the workpiece 15 may be an elongated sheet metal workpiece of the type having a substantially flat web or sheet portion 15a and longitudinal edge flanges 15b extending along one or both side edges thereof. Fig. 14 shows the workpiece 15 in edge view, prior to the bending thereof.

When the improved bending machine 10 is provided with only one of the bending heads, such as the bending head 13, a single bend is formed in the workpiece 15 during each bending operation. Fig. 15 shows the workpiece 15 after the first bend 16 has been formed therein. Figs. 16 and 17 show the same workpiece after the second and third bends 17 and 18 have been formed therein. Fig. 18 shows the same workpiece after the fourth bend 19 has been formed therein and at which time this particular workpiece will have a substantially closed rectangular box-like shape.

When the improved bending machine 10 is provided with the above-mentioned pair of bending heads 13 and 14, two bends 20 and 21 can be formed simultaneously in the workpiece 15 at spaced points and Fig. 19 shows the workpiece after two such bends have been formed therein during the first bending operation. Fig. 20 shows the same workpiece after the second pair of bends 22 and 23 have been formed therein and at which time the workpiece has the same closed rectangular box-like shape as is shown in Fig. 18.

During the bending operations performed by the machine 10 for producing the bends just mentioned with either two bending heads or with a single bending head, the web portion 15a of the workpiece is bent out of its own plane and the flange or flanges 15b of the workpiece are simultaneously bent within their own planes and the bending of these flanges is carried out substantially without wrinkling or buckling.

The base 11 is here shown as comprising a substantially box-like structure adapted to stand on a floor or other supporting surface and has a pair of ways or bearing strips 24 and 25 thereon adjacent the top thereof and which extend transversely of the machine and along the upper side edges of the base. Outwardly of the ways 24 and 25 the base 11 is also provided adjacent the top thereof with racks 26 and 27 which also extend transversely of the machine.

The workholding means 12 comprises an upright plate-like bracket 28 extending longitudinally of the machine and located substantially at the transverse vertical midplane of the base 11 and which bracket is secured to the base as by means of the clamping bolts 29. The bracket 28 preferably includes arm portions 28a and 28d which extend upwardly and outwardly at the front and rear of the machine (see Fig. 6). The expression "front" is used to designate the side of the machine seen in Fig. 3, which is the side on which the machine operator would ordinarily

stand during the performance of the bending operation described hereinafter. The workholding means 12 also includes a stationary lower clamping member 30 carried by the bracket 28 and on which the workpiece 15 is adapted to be received. An upper clamping member 31 is engageable with the upper face of the workpiece between the flanges 15b thereof and is carried by an actuating arm 32 which extends transversely of the machine and is located to lie substantially in the same vertical plane as the transverse bracket 28.

The arm 32 is mounted on the arm portion 28d of the bracket 28 for vertical swinging movement by having one end thereof pivotally journaled on a pivot pin 33 which is carried by the arm portion 28d. At its opposite end the arm 32 is provided with a reduced end portion 32a adapted to be engaged in the opening of a hollow retaining link 34 when the clamping member 31 is in a work-engaging position, as shown in full lines in Fig. 4. The retaining link 34 is mounted on the arm portion 28a of the bracket 28 by the pivot means 35 and is adapted to be swung upwardly to a retaining or locking position in which the reduced end portion 32a engages in the opening of this hollow link.

A lever 36 pivotally connected with the free end of the link 34 by the pivot pin 34a provides an operating handle by which the link can be swung to and from its engaged position. The lever 36 is provided at the pivoted end thereof with an eccentric portion 36a which exerts a camming force on the arm 32 when this lever is swung to its locked position, as shown in Fig. 4, thereby causing the upper clamping member 31 to engage and firmly press the workpiece 15 against the stationary lower clamping member 30. A tension spring 37 having one end suitably anchored on the bracket 28 and its other end connected with the pivoted end of the arm 32 applies a force to the arm 32 tending to swing the same upwardly to the dotted line work-releasing position of Fig. 4 when the retaining link 34 has been swung outwardly and downwardly to its unlocked position.

The tangent bending heads 13 and 14 are substantially identical in construction, except that they are right- and left-hand respectively, and are mounted on the base 11 adjacent opposite ends thereof and in back-to-back relation to each other. Since these tangent bending heads are of the same construction, a detailed description for one of the heads, such as the head 13, will suffice for both of them.

As shown in the drawings the tangent bending head 13 comprises a carriage 39 mounted on the base 11 and a frame 40 mounted on such carriage. The head 13 also includes a wing 41 which is pivoted on the frame 40 for swinging movement and a set of dies comprising a clamping and work supporting die member 42, an anvil die member 43 and a bending die member 44. The clamping die 42 is here shown as being a stationary die carried by the frame 40 and the anvil die 43 is shown as being a movable die which cooperates with the die 42 for clamping the workpiece therebetween. The bending die 44 is also a movable die and is carried by the wing 41 which imparts movement thereto for rocking the bending die around the anvil die 43. The bending die 44 is not mounted directly on the wing 41 but, for a purpose which will appear hereinafter, the bending head 13 is provided with a die carrier 45 which is adapted for translatory

movement relative to the wing and on which the bending die is mounted.

The carriage 39 comprises a generally flat rigid structure of a substantially quadrangular plan shape having a pair of flat bearing surfaces 46 and 47 on the underside thereof and extending along the side edges of the carriage and which bearing surfaces are slidably operable on the ways 24 and 25 of the base 11. The carriage 39 is also provided on the top thereof with a pair of mounting surfaces 48 and 49 on which the frame 40 is mounted and secured as by means of the screws 50. At the point of engagement with the carriage 39 the frame 40 is preferably provided with the pads 51 and 52. Separation of the bearing surfaces 46 from the ways 24 and 25 can be prevented by laterally projecting retaining plates 53 and 54 which are mounted on the carriage so as to extend under and engage the lower surfaces of the ways 24 and 25.

The carriage 39 is also provided with a positioning shaft 53 which extends longitudinally of the machine and is journaled in suitable bearings carried by the carriage at the opposite sides thereof. A pair of pinions 54 and 55 are secured to the shaft 53 to be rotated thereby and mesh with the racks 26 and 27. A handwheel 56 secured to the front end of the shaft 53 provides a means for imparting rotation to this shaft and to the pinions mounted thereon. The rotation of the shaft 53 and pinions 54 and 55 in a clockwise direction, as seen in Fig. 3, will cause the tangent bending head 13 to be shifted toward the right along the ways 24 and 25 of the base 11 and rotation in a counter-clockwise direction will cause the head 13 to be shifted toward the left along the ways 24 and 25. The slidably mounted carriage 39 and the actuating means therefor thus provides an adjusting or positioning means for the tangent bending head 13 by which this head can be shifted relative to the workholding means 12 for determining the different locations on the clamped workpiece 15 at which the bends are to be formed therein.

The frame 40 of the tangent bending head 13 comprises a rigid longitudinal frame portion 40a extending across the base 11 and mounted on the carriage 39 as mentioned above, and an upright frame portion 40b which is integrally connected with the longitudinal frame portion 40a at the rear end thereof, in this instance the right-hand end as seen in Fig. 1, and is located in outwardly offset overhanging relation to the base 11. As shown in Figs. 1 and 2, the frame portion 40a is of a greater length than the width of the base 11 such that its end portions project laterally in overhanging relation to the base. At the extreme outer edges of these overhanging portions the frame 40 is provided with upwardly extending bracket portions 59 and 60 on which the wing 41 is pivotally mounted. The upright frame portion 40b is a generally flat or plate-like portion which is integrally connected with the upright bracket portion 60, as well as with the longitudinal frame portion 40a. The upright frame portion 40b provides a mount on which a pair of power cylinders 62 and 63 are located and which cylinders serve a purpose to be presently explained.

The wing 41 comprises a generally flat plate-like rigid structure 41a extending longitudinally of the machine and a pair of arm portions or brackets 64 and 65 integrally connected with such plate-like structure at opposite ends thereof and located just inwardly of the upwardly extend-

ing bracket portions 59 and 60 of the frame 40. The brackets 64 and 65 provide mounting arms by which the wing 41 is pivotally mounted on the bracket portions 59 and 60 of the frame 40. The bracket portions 59 and 60 of the frame 40 have pivot members or stub shafts 66 and 67 mounted therein (see Figs. 1 and 11) and which carry journal portions 66a and 67a on which the brackets 64 and 65 of the wing 41 are pivotally mounted. As shown in Fig. 1 the brackets 64 and 65 of the wing 41 are provided with guideways 68 and 69 in which the side edges of the die carrier 45 are slidably operable, as further explained hereinafter.

As best seen in Figs. 1 and 7, the work supporting and clamping die 42 is a substantially flat plate-like member extending longitudinally of the machine and mounted on a flat longitudinal ledge portion 70 of the frame 40. The die 42 is a stationary die member against which the web portion 15a of the workpiece is adapted to be clamped by the anvil die 43 for the bending operation. As shown in Figs. 1, 2 and 7, the anvil die 43 also extends longitudinally of the machine and has a substantially flat bottom surface 43a which engages the web portion of the workpiece 15 for clamping the same against the stationary die 42. The anvil die 43 is also provided with a convexly curved portion 43b on the outer side thereof having a contour or radius of curvature corresponding with the bend desired to be formed in the workpiece 15.

The anvil die 43 is movable toward and away from the die 42 for clamping and releasing the workpiece 15 and, for this purpose, the anvil die is carried and actuated by an arm 71 extending longitudinally and forwardly of the machine at a point above the die 42. As shown in Figs. 1 and 5, the arm 71 is a lateral extension of a vertically elongated generally flat slide 72 which is operable in a guideway 73 provided on the rear or inner side of the upright frame portion 40b. This guideway 73 is formed, in part, by a pair of strip members 74 and 75 which are mounted on the rear side of the upright frame portion 40b and attached thereto by the screws 76.

At its extreme forward (left) end the arm 71 is provided with a reduced portion 77 (see Fig. 1) adapted to be engaged by a locking device formed by a hollow retaining link 78 and a lever 79. When the slide 72 has been moved downwardly, in the manner to be explained hereinafter, to cause the workpiece 15 to be clamped against the die 42 by the anvil die 43, the end portion 77 of the arm 71 will be in a position to be engaged by the link 78. As shown in Fig. 3 of the drawings, the link 78 is hollow to permit the reduced end portion 77 to engage in the opening thereof and this link has its lower end connected to the upright bracket portion 59 of the frame 40 by a pivot member 80. The lever 79 is connected to the free end of the link 78 by a pivot member 81 and has an eccentric portion 82 thereon which cooperates with the reduced end portion 77 when the link has been swung to its retaining position and the lever 79 has been rocked on the pivot member 81 to assume the full line locked position shown in Fig. 1.

The bending die 44 comprises a generally flat plate-like member extending longitudinally of the machine and which is somewhat longer than the anvil die 43. This bending die is suitably connected to the carrier 45 and has a substantially flat working face 44a on the upper side thereof which is tangentially rockable around

the curved outer portion 43b of the anvil die 43 during swinging of the wing 41 on the pivot shafts 66 and 67. During this tangential rocking of the bending die 44 around the anvil die 43, the flat surface 44a cooperates with the curved surface 43b in bending the workpiece 15 therearound to form the bend 20 therein and causes the workpiece to assume the bent condition shown in Fig. 7. The view of Fig. 7 shows the wing 41 and bending die 44 in their initial position in full lines and also shows these members in dotted lines at the completion of the bending operation.

The bending die 44 includes inserts 83 and 84 of an angular cross-section and made of hardened material. These inserts are located adjacent the ends of the bending die and cooperate with hardened strip end portions 85 and 86 provided on the anvil die 43. The cooperating inserts 83, 84 and strips 85, 86 confine the flanges 15b of the workpiece therebetween and hold such flanges against wrinkling or buckling during the bending operation. The anvil die 43 is of a length such that when engaged with the web portion 15a of the workpiece 15 it will extend between the flanges 15b so as to locate the hardened strip portions 85 and 86 in cooperating relation to the hardened inserts 83 and 84 of the bending die 44.

The carrier 45 on which the bending die 44 is mounted is a generally flat plate-like member having its ends extending into and slidably in the guideways 68 and 69 of the wing 41, as mentioned above. As shown in Figs. 1 and 9, the wing 41 is provided on the upper side thereof with laterally spaced bearing strips 87 on which the carrier 45 is slidable. The bearing strips 87 are preferably not secured to the wing 41 but are mounted in shallow grooves 88 thereof so as to be capable of limited movement in such grooves in a direction substantially normal to the plane of the wing.

When the die carrier 45 is mounted on the wing 41 in the manner just described, it will be seen that this member is capable of translatory movement relative to the wing during the swinging movement of the latter. During this translatory movement the carrier 45 slides on the bearing strips 87 and in the guideways 68 and 69. These guideways are of such width in a vertical direction as seen in Fig. 1, as to permit some limited shifting of the carrier 45 in a direction substantially normal to the plane of the wing 41. This shifting movement of the carrier in the guideways 68 and 69 permits the carrier to produce a corresponding limited movement of the bending die 44 relative to the anvil die 43 for causing the workpiece 15 to always be pressed tightly against the anvil die by the bending die.

For causing the bending die 44 to exert a desired continuous pressure against the workpiece 15 during the bending operation, the wing 41 is also provided with a plurality of compression springs 89 disposed in pockets 90 thereof which are located immediately under the bearing strips 87. These compression springs apply pressure to the carrier 45 through the bearing strips for pressing the bending die 44 and the workpiece 15 against the anvil die 43, as just explained above. As best seen in Fig. 9, each of the springs 89 is provided with a seat 91 at one end thereof for applying the pressure of the spring to the bearing strip 87 and at its other end is provided with a seat 92 which is adjustably movable in the pocket

90 by means of an adjusting screw 93 for varying the compression of the spring 89. The pressure with which the bending die 44 presses the workpiece 15 against the anvil die 43 during the bending operation is thus a continuous pressure which will enable the bending die to produce a smooth bending of the workpiece around the curved anvil die portion 43b and the occurrence of wrinkles or other irregularities in the bend being formed will be avoided.

The opening and closing movements of the anvil die 43 relative to the work supporting and clamping die 42 for clamping or releasing the workpiece 15 are produced by corresponding downward and upward vertical movement of the slide 72 in the guideway 73 of the overhanging upright frame portion 40b. Actuation of the slide 72 for this purpose is produced by the power cylinder 63. The upper end of this power cylinder is provided with a forked portion 94 which is pivotally connected with a laterally projecting bracket 95 of the frame portion 40b by means of a pivot pin 96.

A piston rod 67 has one end connected with a double-acting piston which is operable in the cylinder 63, as by hydraulic pressure supplied thereto, and its outer end carries a forked member 98. This forked member is connected with a laterally projecting bracket 99 of the slide 72 by means of a pivot pin 100. The upright frame portion 40b is provided with a vertically extending slot 101 through which the bracket 99 of the slide projects and which permits upward movement of the slide to the dotted line position shown in Fig. 1 and corresponding with the open position of the anvil die 43.

The swinging movement of the wing 41 for actuating the bending die 44 is imparted thereto by the double-acting power cylinder 62 to which hydraulic pressure fluid can be appropriately supplied. This power cylinder is provided at the lower end thereof with a forked member 102 which is pivotally connected with a laterally projecting bracket 103 of the upright frame portion 40b by means of the pivot pin 104. A piston rod 105 has one end thereof connected with a piston which is operable in the cylinder 62 and at its other end is provided with a head 106 which is pivotally connected with the wing 41. For the purpose of this pivotal connection the wing is provided at the right-hand side thereof with an integral bracket or boss 107 and with a pivot pin or stud 108 carried by such boss and extending through a pivot opening of the head 106.

The above-mentioned translatory movement for the carrier 45 relative to the wing 41 is a very important characteristic of this improved bending machine because it controls and, if circumstances require it, modifies the working travel of the bending die 44 during the tangential rocking thereof around the curved portion of the anvil die 43. This translatory movement of the bending die causes it to travel around the anvil die with a true rocking movement which is substantially devoid of relative slipping and with the bending die acting at all portions of such rocking movement to press and form the workpiece tightly against the anvil die. This true rocking movement for the bending die 44 results in a tangent bending operation which produces a smooth and accurate bend in the workpiece with a minimum of spring-back effect and substantially without slipping or chattering between the die members such as might produce wrinkling or tearing or other irregularities in the workpiece. This com-

ponent of translatory movement imparted to the bending die 44 is produced by a positive and direct actuation of the carrier 45 by a mechanism which will now be described.

5 The mechanism for producing the translatory movement of the carrier 45 relative to the wing 41 includes a rock shaft 110 carried by the wing and actuating mechanism 111 for imparting an arcuate or rotary movement to this shaft during 10 the swinging of the wing. The rock shaft 110 is here shown as extending longitudinally of the wing 41 and transversely of the base 11 and located on the underside of the wing. The rock shaft is mounted on the wing by having end portions 15 thereof journaled in suitable bearing brackets 112 and 113 carried by the wing and depending therefrom. At the left side of the wing, as seen in Fig. 1, the rock shaft 110 has an end portion 114 which projects outwardly beyond the bearing bracket 112 for operative connection with the rock shaft actuating mechanism 111.

For operably connecting the carrier 45 with the rock shaft 110, the latter is provided with collars 115 and 116 which are secured thereto and carry 25 gear sectors 117 and 118 having meshing engagement with racks 119 and 120 provided on the underside of the carrier adjacent the side edges thereof. At the location of the gear sectors 117 and 118, the wing 41 is provided with openings 121 and 122 which accommodate these gear sectors and by which the racks 119 and 120 are exposed for meshing engagement by the gear sectors.

35 The actuating mechanism 111 for imparting the rocking movement to the rock shaft 110 is here shown as being of the reaction type utilizing relative movement between the wing 41 and the frame 40. This mechanism comprises a pair of 40 levers 123 and 124 and a thrust link 125 extending therebetween. The lever 123 is keyed or otherwise secured to the outwardly projecting end portion 114 of the rock shaft 110 and carries a portion 126 having a journal portion 126a on which one end of the link 125 is pivotally mounted.

45 The lever 124 is not a movable lever but is more in the nature of a bracket or quadrant as this member is rigidly mounted on the upwardly extending bracket portion 59 of the frame 40. As shown in Figs. 3 and 11, the frame portion 59 is provided with a boss or pad 127 to which the large end 124a of the lever 124 is secured by means of the screws 128 with a spacer 129 interposed between such large end and the boss. The spacer 129 also forms a cover and anchoring means (see Fig. 11) for the wing pivot shaft 66 which is connected therewith by means of the screw 130. The lever 124 is provided with an arcuate slot 131 in which is mounted a two-part bracket 132 carrying a pivot pin 133 on which the other end of the link 125 is pivotally mounted. The bracket 132 comprises cooperating parts 132a and 132b adapted to be drawn together into clamping engagement with the lever 124 from opposite sides thereof by the clamping screw 134.

60 It is important to note in connection with the lever 124 that the center line 135 of the arcuate slot 131 intersects the pivot axis of the wing shafts 66 and 61. By loosening the screw 134 the clamping pressure of the bracket parts 132a and 132b can be relieved so that this bracket can be shifted along the slot 131 to different desired positions for varying the eccentricity of the pivot pin 133 with respect to the pivot axis of the wing. 70 By then tightening the clamping screw 134 the

11

bracket parts 132a and 132b will grip the lever 124 for maintaining the pivot pin 133 at the desired position of adjustment.

When the pivot pin 133 has been adjusted to the position of maximum eccentricity, as shown in Fig. 3, the lever 124 will act as a stationary crank and will cause the maximum amount of movement to be transmitted through the link 125 and lever 123 to the rock shaft 110 during the swinging of the wing for the bending operation. When the pivot pin 133 has been adjusted to a position in which its pivot axis coincides with the pivot axis of the wing, the eccentricity will be zero and the lever 124 will be ineffective as a crank arm and no movement will be transmitted through the link 125 to the rock shaft 110.

From the construction and brief operating description above given for the mechanism 111 it will be seen that this mechanism is a reaction mechanism by which reaction thrust will be applied to the rock shaft 110 to cause a desired rocking movement thereof during the upward swinging of the wing 41 in carrying out a bending operation on the workpiece 15. The extent of this rocking movement of the shaft 110 will be in accordance with the setting of the pivot pin 133, as just explained above, and will cause a corresponding extent of translatory sliding movement of the carrier 45 relative to the wing. The reaction thrust thus supplied to the carrier 45 during the swinging of the wing 41 produces the above explained component of translatory movement for the bending die 44 during its working travel around the anvil die 43 and by which the above described highly satisfactory bending operation is accomplished on the workpiece 15. This component of translatory movement imparted to the bending die 44 causes the working travel of this die to be adapted to the curvature of the anvil die which is being used in the machine for the work shape desired to be produced, such that the bending die will have the above-explained true tangential rocking movement on the anvil die. The reaction thrust mechanism 111 can thus be adjusted to the proper eccentric setting for the shape or curvature of the particular anvil die being used in the machine and such setting will cause a component of translatory movement to be imparted to the bending die during the swinging of the wing, by which the true tangential rocking of bending die for accurate bending of the workpiece around the anvil die, will be obtained without need for the radius gears heretofore employed. When the machine 10 is being set up for the production of a particular workpiece it is only necessary to substitute an anvil die of the proper shape or curvature in the machine and then adjust the eccentricity of the reaction mechanism 111 to adapt the tangential rocking travel of the bending die to this anvil die shape.

When the bending machine 10 is provided with the two tangent bending heads 13 and 14, the two bends 20 and 21 can be formed in the workpiece 15 simultaneously. Likewise, the two subsequent bends 22 and 23 can be formed in this workpiece simultaneously by the heads 13 and 14 after they have been shifted into a more closely spaced relation by manipulation of the handwheels 56. For properly locating the heads 13 and 14 on the base 11 for the formation of the pairs of bends 20, 21 and 22, 23 in the workpiece at the desired locations, suitable positioning selecting devices or stop means can be provided.

In this instance, this stop means comprises a

12

rock shaft 136 mounted on the base 11 and a pair of collars 137 and 138 mounted on this shaft for each of the bending heads 13 and 14. This stop means also includes a stop plate 139 mounted on the carriage 39 and having a depending rib 139a for cooperation with the collars 137 and 138. When the heads 13 and 14 are shifted along the ways 24 and 25 of the base 11 to their outermost position relative to the workholding means 12, as shown in Figs. 2, 3 and 7, the outer end of the depending rib 139a will engage the stop collar 137 and thus accurately locate the heads 13 and 14 at the proper position for the formation of the first pair of bends 20 and 21 in the workpiece 15.

Preparatory to forming the second pair of bends in the workpiece, the heads 13 and 14 are moved inwardly toward the workholding device 12 to the setting represented by the center lines 140 of Fig. 7 by manipulation of the handwheels 56. This inner position for the heads 13 and 14 is determined by the abutting engagement of the inner end of the stop ribs 139a with the end face 138a of the stop collars 138 of the shaft 136. When this abutting engagement takes place the heads 13 and 14 will be in their proper setting for forming the second pair of bends 22 and 23 at the proper location in the workpiece 15.

When the second pair of bends has been completed, it is desirable to shift the bending heads 13 and 14 still closer together by movement inwardly to a third setting or unloading position represented by the center line 141 of Fig. 7. The movement of the bending heads to this position permits the flanges 15b of the workpiece to clear the bending dies for removal of the workpiece from the machine. To permit this final inward movement of the bending heads 13 and 14 to the unloading position represented by the center lines 141, the stop collars 138 are provided with recesses 142 of a depth corresponding with or slightly greater than the depth of the flanges 15a of the workpiece. By an arcuate movement of the shaft 136 after the second bending operation the stop collars 138 will be shifted to a position in which the inner ends of the stop ribs 139 will engage in the recesses 142, thereby permitting movement of the bending heads 13 or 14 to the final or unloading position represented by the center lines 141 and at which the workpiece 15 can be removed from the machine.

The arcuate movement of the shaft 136, which is needed for moving the notches 142 of the stop collars 138 into and out of position for cooperation with the stop ribs 139a, can be imparted to this shaft by an operating lever 143 having a handle portion 143a at its outer end which projects laterally beyond the frame 11 at the front of the machine as seen in Figs. 1 and 2. The inner end of the lever 143 can be pivotally mounted on the base 11 by a suitable pivot pin 144. At an intermediate point thereof the lever 143 is operably connected with the shaft 136 by a link 145 and a lever 146 which is keyed or otherwise fixed on the shaft. The operating lever 143 is preferably located at the front of the base 11 and the connecting lever 146 is mounted on an end portion of the shaft 136 which projects outwardly at the front of the base.

A suitable latch device 147 (see Figs. 3 and 12) can be provided on the base 11 for cooperation with the handle portion 143a for normally retaining the lever 143 in its full line position of Fig. 1 which corresponds with the setting of the

stop collars 138 shown in Fig. 2 in which their notches 142 are in their ineffective position. In their position of Fig. 2 the stop collars 138 are in readiness for their end faces 138a to be engaged by the rib 139a for locating the bending heads 13 and 14 for the second pair of bends, as explained above, and it is desirable to maintain these stop collars in this position until the workpiece is to be removed from the machine. Accordingly, the latch device 147 includes a latch member 148 mounted on a pivot pin 149 and a weight 150 connected with the latch member and disposed in such overhanging relation to the pivot pin 149 as to releasably hold the latch member in the position shown in Figs. 3 and 12.

The latch device 147 also includes a mounting plate 147a which is suitably attached to the base plate 11 and, in addition to having the pivot pin 149 10 mounted thereon, this plate carries a pair of stop pins 149a and 149b. The latch member 148 has pins 149a and 149b. The latch member 148 has a lug 148a at the upper end thereof which has a straight top edge and which lug extends into the path of downward movement of the handle portion 143a to prevent such downward movement until the stop collars 138 are to be shifted to 15 locate their notches 142 in an effective position to receive the rib 139a. The latch member 148 also has a projecting finger 148b thereon which engages the stop pin 149a when the latch member is being held by the weight 150 in the position shown in Figs. 3 and 12 in which the lug 148a extends into the path of downward movement of the lever 143. An upwardly and forwardly sloping bevel 148c provided on the latch member 148 just below the lug 148a permits the lever 143 to 20 be readily moved upwardly past the latch member for returning the stop collars to their initial setting of Fig. 2. During this upward movement of the lever 143 past the bevel 148c, the latch member 148 swings on the pivot pin 149 and such swinging is limited in extent by the stop pin 149b.

From the foregoing description of the improved bending machine 10 and the illustration thereof in the drawings, it will be observed that the co-operating arm and bracket parts 32 and 28 of the workholding means 12 and the arms 71 of the bending heads 13 and 14 in cooperation with the work supporting die members 42 provide gaps into which the workpiece 15 can be readily inserted from the front of the machine which is at the left side as seen in Figs. 1 and 2. It will also be observed that the handwheels 56, the lever 36 of the workholding means 12 and the levers 79 of the bending heads 13 and 14, as well as the lever 143 of the stop means, are all located at the front of the machine so as to be readily accessible to the workman who inserts the workpiece into the gap or gaps of the machine.

The operation of the improved bending machine 10 can be best described by following through a cycle of operation in performing the desired bends in the workpiece 15. In describing this cycle of operation it will be assumed that the machine 10 includes the two bending heads 13 and 14; that these heads are initially at the setting shown in Fig. 3; that the arm 32 of the workholding means 12 is in its dotted line open position of Fig. 6; and that the power cylinders 63 have been actuated to move the anvil dies 43 to their dotted line open position shown in Fig. 1. The operator then inserts the workpiece 15 into the machine with an intermediate portion thereof received between the clamping members 30 and

31 of the workholding means 12 and with the opposite end portions of the workpiece extending away from the workholding means and through the bending heads 13 and 14 so as to lie between the paired work supporting die 42 and the anvil die 43 of the latter.

When the workpiece is in this position the operator swings the arm 32 of the workholding means 12 downwardly so as to clamp the intermediate portion of the workpiece between the members 31 and 30. The operator then moves the link 34 and the lever 36 to the locked position shown in Fig. 4. With the workpiece thus gripped at its intermediate point in the machine, the operator then energizes the power cylinders 63 to actuate the slides 72 of the bending heads 13 and 14 downwardly, thereby causing the anvil die members 43 to move into clamping cooperation with the work supporting dies 42 and clamp the workpiece against the latter, as shown in Fig. 7.

The operator now energizes the power cylinders 62 to impart an upward swinging movement to the wings 45 of the bending heads 13 and 14. During this upward swinging movement the bending dies 44 are rocked tangentially around the curved portions 43b of the anvil die members 43 to form the bends 20 and 21 in the workpiece. During this upward swinging of the wings 41 the reaction mechanisms 111 impart the above described rocking movement to the rock shaft 110 for producing the translatory sliding movement of the carriers 45 relative to the wings. As already explained above, this relative translatory movement for the carriers 45 imparts a component of translatory movement to the bending dies 44 during the bending operation for causing the desired true tangential rocking of the bending dies on the anvil die members.

After the bends 20 and 21 have been thus produced in the workpiece 15, the power cylinders 62 are actuated to return the wings 41 to their initial position shown in full lines in Figs. 1 and 7. Next the operator actuates the power cylinders 63 to move the slides 72 and the anvil die members 43 upwardly to release the clamping action of the anvil die members on the workpiece. Preparatory to forming the second pair of bends 22 and 23 in the workpiece, the operator manipulates the handwheels 56 to shift the bending heads 13 and 14 inwardly to the second bending position represented by the center lines 140. The operator then again energizes the cylinders 63 to move the slides 72 downwardly to cause the anvil die members 43 to reclamp the workpiece against the work supporting dies 42. The links 78 and the levers 79 of the heads 13 and 14 are then shifted to their locked position on the arms 71, as shown in Fig. 1. The operator then again energizes the power cylinders 62 for swinging the wings 41 upwardly to produce the second pair of bends 22 and 23 in the workpiece.

Upon the completion of the second pair of bends the cylinders 62 are actuated to return the wings to their initial position and the power cylinders 63 are actuated to move the anvil die members 43 upwardly to the work-releasing position. Next the operator actuates the lever 143 to rock the shaft 136 and thus shift the stop collars 142 to 70 permit the bending heads 13 and 14 to be moved further inwardly to the unloading position represented by the center lines 141 and which is accomplished by further manipulation of the handwheels 56. The operator then disengages the retaining link 34 from the arm 32 and permits the

latter to swing to its released dotted line position under the influence of the tension spring 37. The formed workpiece can then be removed from the front of the machine by the operator and another workpiece substituted in its place preparatory to the above explained cycle of operation being repeated.

When the machine 10 is provided with only a single bending head, such as the bending head 13, all four of the bends 16, 17, 18 and 19 of the workpiece 15 as shown in Figs. 14 to 17 inclusive, are formed by this one head.

In Fig. 13 of the drawings a construction is shown for the machine 10 in which an anvil die member 152 of a different shape has been substituted for the anvil die member or members 43. The anvil die 152 differs from the die 43 in that it does not have a convexly curved portion but has substantially flat front and bottom faces 153 and 154 which intersect along a line forming a relatively sharp corner 155 on this die. An anvil die of this shape is suitable for carrying out a bending operation in which the workpiece 156 is bent around the anvil die by a bending die 157 so as to form a sharp bend in the workpiece such as the substantially ninety degree bend shown in Fig. 13.

In other respects the bending machine illustrated in Fig. 13 is substantially identical with the bending machine shown in Figs. 1 to 12 inclusive. When the modified anvil die 152 is used, the reaction thrust mechanism 111 is adjusted to its ineffective position by shifting the pivot pin 134 to the position of zero eccentricity in which its pivot axis coincides with the pivot axis of the wing 41. At this time the carrier 45 will be held against translatory sliding movement relative to the wing by the rock shaft 110 and the gear sectors 117 and 118 carried thereby.

It will be understood, of course, that the anvil die 152 represents only one of the various other shapes which can be substituted in the machine 10 for the anvil die members 43. In some cases the substituted anvil die members will have a convexly curved working face of a relatively flatter radius of curvature than the die 43 and, in those cases, the pivot pin 133 of the reaction mechanism 111 would be set at corresponding positions having eccentricity values between the maximum value setting shown in Fig. 1 for the anvil die 43 and the zero value setting shown in Fig. 13 for the anvil die 152.

From the foregoing description and the accompanying drawings it will now be readily understood that this invention provides an improved bending machine of the tangent bender type which will be very rugged and durable in service, will be relatively easy to operate and will perform a highly satisfactory bending operation on a flanged workpiece by bending a web portion of the workpiece out of its own plane and simultaneously bending a flange portion of the workpiece within its own plane without wrinkling or buckling of such flange portion. It will also be seen that this invention provides an improved tangent bender of this type having multiple bending heads which can be readily shifted to different positions relative to a work-holding device for producing the bends in the workpiece at the desired locations. Additionally, it will be seen that this machine is adaptable for use with either one or two of such tangent bending heads and can thus be built and sold at a very economical price which will bring a bending machine of this type and having a wide range

of usefulness within the reach of numerous small manufacturing establishments having limited money resources.

It will also be seen that this improved machine provides novel means for introducing into the tangential rocking movement of the bending die a component of translatory movement such that the bending die will always cooperate with its anvil die with a true tangential rocking thereon for producing a smooth, accurate and satisfactory bend in the workpiece. Likewise, it will be seen that this invention provides novel actuating means for a die carrier having a translatory movement relative to the wing, such that reaction thrust will be utilized to impart this translatory movement to the carrier and bending die in response to the swinging of the wing relative to the frame. A further important advantage for this improved machine resides in the novel means provided for adjustment of the reaction mechanism to different values of eccentricity for adapting the working movement of the bending die to suit the shape or curvature of the particular anvil die member being used in the machine.

Although the improved bending machine of the present invention has been illustrated and described herein to a detailed extent, it will be understood, of course, that the invention is not to be regarded as being limited correspondingly in scope but includes all changes and modifications coming within the terms of the claims hereof.

Having thus described my invention, I claim:

1. In a metal bending machine, a stationary frame, a pair of cooperating dies adapted to receive and clamp therebetween a workpiece to be bent and one of which dies is an anvil die, a wing having a die carrier supported thereon for translatory movement relative thereto, a bending die mounted on said die carrier, means mounting said wing on said frame for swinging movement for causing rocking of said bending die relative to said anvil die for bending the workpiece around the latter, means for imparting said swinging movement to said wing, means pivotally mounted on said wing and having an operative thrust-transmitting connection with die carrier for imparting said translatory movement thereto, and reaction thrust linkage having one end thereof anchored on said frame and its other end connected with such pivotally mounted means for applying thrust to the latter in response to the swinging of said wing.

2. In a metal bending machine, a frame, a pair of cooperating dies adapted to receive and clamp therebetween a workpiece to be bent and one of which dies is an anvil die, a wing having a die carrier supported thereon for translatory movement relative thereto, a bending die mounted on said die carrier, pivot means mounting said wing on said frame for swinging movement for causing rocking of said bending die relative to said anvil die for bending the workpiece therearound, means for imparting said swinging movement to said wing, means pivotally mounted on said wing and having an operative thrust-transmitting connection with said die carrier for imparting said translatory movement thereto, reaction thrust linkage having one end thereof connected with such pivotally mounted means for applying thrust thereto during the swinging of said wing, and means for pivotally anchoring the other end of said linkage on said frame substantially on the axis of said pivot means.

3. In a metal bending machine, a frame, a pair of cooperating dies adapted to receive and clamp therebetween a workpiece to be bent and one of which dies is an anvil die, a wing having a die carrier supported thereon for translatory movement relative thereto, a bending die mounted on said die carrier, pivot means mounting said wing on said frame for swinging movement for causing rocking of said bending die relative to said anvil die for bending the workpiece therearound, means for imparting said swinging movement to said wing, means pivotally mounted on said wing and having an operative thrust-transmitting connection with said die carrier for imparting said translatory movement thereto, reaction thrust linkage having one end thereof connected with such pivotally mounted means for applying thrust thereto during the swinging of said wing, and means for pivotally anchoring the other end of said linkage on said frame including means permitting adjustment of the eccentricity of the anchor point with respect to the axis of said pivot means.

4. In a metal bending machine, a frame, a pair of cooperating dies adapted to receive and clamp therebetween a workpiece to be bent and one of which dies is an anvil die, a wing having a die carrier supported thereon for translatory movement relative thereto, a bending die mounted on said die carrier, pivot means mounting said wing on said frame for swinging movement for causing rocking of said bending die relative to said anvil die for bending the workpiece around the latter, means for imparting said swinging movement to said wing, means pivotally mounted on said wing and having an operative thrust-transmitting connection with said die carrier for imparting said translatory movement thereto, reaction thrust linkage having one end thereof connected with such pivotally mounted means for applying thrust thereto during the swinging of said wing, a bracket connected with said frame and having an arcuate slot lying on a line which intersects the axis of said pivot means, a member adjustable along said slot to different positions of eccentricity relative to said pivot axis and adapted to be clamped to said bracket at the desired adjustment, and means pivotally connecting the other end of said linkage with said member.

5. In a metal bending machine, a stationary frame, a pair of cooperating dies adapted to receive and clamp therebetween a workpiece to be bent and one of which dies is an anvil die, a wing having a guideway thereon, a die carrier operable in said guideway for translatory movement relative to said wing, a bending die mounted on said die carrier, pivot means mounting said wing on said frame for swinging movement for causing rocking of said bending die relative to said anvil die for bending said workpiece around the latter, means for imparting swinging movement to said wing, a rock shaft mounted on said wing, means forming an operative connection between said rock shaft and said die carrier for causing said translatory movement of the latter along said guideway in response to rocking movement of the rock shaft, and reaction thrust linkage having one end thereof anchored on said frame and its other end connected with said rock shaft and operable to impart rocking movement to said rock shaft in response to the swinging of said wing.

6. In a metal bending machine, a stationary frame, a pair of cooperating dies adapted to re-

ceive and clamp therebetween a workpiece to be bent and one of which dies is an anvil die, a wing having a guideway thereon, a die carrier operable in said guideway for translatory movement relative to said wing, a bending die mounted on said die carrier, pivot means mounting said wing on said frame for swinging movement for causing rocking of said bending die relative to said anvil die for bending said workpiece around the latter, means for imparting swinging movement to said wing, a rock shaft mounted on said wing, means forming an operative connection between said rock shaft and said die carrier for causing said translatory movement of the latter along said guideway in response to rocking movement of the rock shaft, reaction thrust linkage having one end thereof anchored on said frame and its other end connected with said rock shaft and operable to impart rocking movement to said rock shaft in response to the swinging of said wing, and pressure means carried by said wing and effective on the underside of said die carrier for pressing said bending die and workpiece against said anvil die.

7. In a metal bending machine, a stationary frame, a pair of cooperating dies adapted to receive and clamp therebetween a workpiece to be bent and one of which dies is an anvil die, a wing having a guideway thereon, a die carrier operable in said guideway for translatory movement relative to said wing, a bending die mounted on said die carrier, pivot means mounting said wing on said frame for swinging movement for causing rocking of said bending die relative to said anvil die for bending said workpiece around the latter, means for imparting swinging movement to said wing, a rock shaft mounted on said wing, a rack on said die carrier, a gear sector forming an operative connection between said rock shaft and said rack for causing said translatory movement of said die carrier along said guideway in response to rocking movement of the rock shaft, and reaction thrust linkage having one end thereof anchored on said frame and its other end connected with said rock shaft and operable to impart rocking movement to said rock shaft in response to the swinging of said wing.

8. In a metal bending machine, a frame, a pair of cooperating dies adapted to receive and clamp therebetween a workpiece to be bent and one of which dies is an anvil die, a wing having a guideway thereon, a die carrier operable in said guideway for translatory movement relative to said wing, a bending die mounted on said die carrier, pivot means mounting said wing on said frame for swinging movement for causing rocking of said bending die relative to said anvil die for bending said workpiece around the latter, means for imparting swinging movement to said wing, a rock shaft mounted on said wing, a rack on said die carrier, a gear sector forming an operative connection between said rock shaft and said rack for causing said translatory movement of said die carrier in response to rocking movement of the rock shaft, a lever on said rock shaft, reaction thrust linkage having one end thereof connected with said lever for imparting rocking movement to said rock shaft during the swinging of said wing, and means for pivotally anchoring the other end of said linkage on said frame including means permitting adjustment of the eccentricity of the anchor point with respect to the axis of said pivot means.

9. In a metal bending machine, a frame, a pair of cooperating dies adapted to receive and clamp

therebetween a workpiece to be bent and one of which dies is an anvil die, a wing having a guideway thereon, a die carrier operable in said guideway for translatory movement relative to said wing, a bending die mounted on said die carrier, pivot means mounting said wing on said frame for swinging movement for causing rocking of said bending die relative to said anvil die for bending said workpiece around the latter, means for imparting swinging movement to said wing, a rock shaft mounted on said wing, a rack on said die carrier, a gear sector forming an operative connection between said rock shaft and said rack for causing said translatory movement of said die carrier in response to rocking movement of the rock shaft, a lever on said rock shaft, reaction thrust linkage having one end thereof connected with said lever for imparting rocking movement to said rock shaft during the swinging of said wing, a bracket connected with said frame and having an arcuate slot lying on an arcuate center line which intersects the axis of said pivot means, a block adjustable along said slot to different positions of eccentricity relative to said pivot axis and adapted to be locked to said bracket at the desired adjustment, and means pivotally connecting the other end of said linkage with said block.

10. A bending machine of the character described comprising, a laterally elongated frame, a pair of laterally elongated dies adapted to receive and clamp therebetween a workpiece to be bent and one of which dies is an anvil die, a laterally elongated wing having guideways adjacent the ends thereof, a laterally elongated die carrier having portions thereof operable in said guideways for translatory movement of said die carrier relative to said wing, a laterally elongated bending die mounted on one side of said die carrier, laterally spaced pivot means mounting said wing on said frame for swinging movement for causing rocking of said bending die relative to said anvil die for bending said workpiece around the latter, means for imparting swinging movement to said wing, a rock shaft mounted on said wing and extending longitudinally thereof, racks on said die carrier adjacent the edges thereof, gear sectors forming an operative connection between said racks and said rock shaft for causing said translatory movement of said die carrier in response to rocking movement of the rock shaft, and actuating means connected with said rock shaft and operable to impart rocking movement thereto during swinging of said wing.

11. A bending machine of the character described comprising, a laterally elongated frame, a pair of laterally elongated dies adapted to receive and clamp therebetween a workpiece to be bent and one of which dies is an anvil die, a laterally elongated wing having guideways adjacent the ends thereof, a laterally elongated die carrier having portions thereof operable in said guideways for translatory movement of said die carrier relative to said wing, a laterally elongated bending die mounted on one side of said die carrier, laterally spaced pivot means mounting said wing on said frame for swinging movement for causing rocking of said bending die relative to said anvil die for bending said workpiece around the latter, means for imparting swinging movement to said wing, a rock shaft mounted on said wing and extending longitudinally thereof, racks on said die carrier at longitudinally spaced points thereof, gear sectors forming an

operative connection between said racks and said rock shaft for causing said translatory movement of said die carrier in response to rocking movement of the rock shaft, actuating means connected with said rock shaft and operable to impart rocking movement thereto during swinging of said wing, and pressure devices carried by said wing and spaced apart longitudinally thereof and effective for applying pressure to said die carrier.

12. In a bending machine of the character described, a laterally elongated base having upright front and rear walls and also having longitudinal front and rear ways extending along the top thereof adjacent the upper edges of said walls, a work clamping device adapted to grip an elongated workpiece extending longitudinally of said base and comprising cooperating upper and lower gripping members supported by said base and extending in a direction transverse to said walls, pivot means located above said rear wall and mounting said upper gripping member for opening and closing swinging movement relative to said lower gripping member and providing for insertion and removal of the workpiece in said clamping device from a front operating station adjacent said front wall, a bending head comprising a frame extending across said base in a direction transverse to said walls and being slidably supported on said ways for movement toward and away from said clamping device, said frame having an extension portion projecting in rearwardly overhanging relation to said base and including an upright portion located adjacent said rear wall and having a substantially greater height than said rear wall, means defining a substantially vertical guideway on said upright portion, a pair of cooperating upper and lower dies extending across said base in a direction transverse to said walls and adapted to receive and clamp therebetween a portion of said workpiece, the lower of said dies being a stationary die mounted on said frame and the upper die being an anvil die and being movable toward and away from said lower die, a slide operable in said guideway and having an arm extending across said base in a direction transverse to said walls and forming a carrier for said anvil die and providing for insertion and removal of said workpiece in said pair of dies from said front operating station, a wing extending across said base in a direction transverse to said walls, a bending die carried by said wing and extending across said base in a direction transverse to said walls and being mounted on said wing for translatory movement relative thereto, pivot means mounting said wing on said frame for upward swinging movement for causing rocking of said bending die relative to said anvil die for bending said workpiece around the latter, a first upright power cylinder means mounted on said upright portion and operably connected with said slide to actuate the same for causing opening and closing movements of said anvil die, a second upright power cylinder means mounted on said upright portion and operably connected with said wing for actuating the wing and said bending die, a pair of front and rear racks mounted on said base and extending longitudinally thereof adjacent said front and rear ways, a shaft rotatably mounted in said frame and extending in a direction transverse to said walls, gear means connected with shaft and engaging said racks for causing movement of said frame along said ways in response to rotation of said shaft.

and shaft rotating means manually accessible to said front operating station.

13. In a bending machine of the character described, a laterally elongated base having upper front and rear walls and also having longitudinal front and rear ways extending along the top thereof adjacent the upper edges of said walls, a work clamping device adapted to grip an elongated workpiece extending longitudinally of said base and comprising cooperating upper and lower gripping members supported by said base and extending in a direction transverse to said walls at an intermediate point of said ways, pivot means located above said rear wall and mounting said upper gripping member for opening and closing swinging movement relative to said lower gripping member and providing for insertion and removal of the workpiece in said clamping device from a front operating station adjacent said front wall, a bending head located on each side of said clamping device, each such bending head comprising a frame extending across said base in a direction transverse to said walls and being slidably supported on said ways for movement toward and away from said clamping device, said frame having an extension portion projecting in rearwardly overhanging relation to said base and including an upright portion located adjacent said rear wall and having a substantially greater height than said rear wall, means defining a substantially vertical guideway on said upright portion, a pair of cooperating upper and lower dies extending across said base in a direction transverse to said walls and adapted to receive and clamp therebetween a portion of said workpiece, the lower of said dies being a stationary die mounted on said frame and the upper die being an anvil die and being movable toward and away from said lower die, a slide operable in said guideway and having an arm extending across said base in a direction transverse to said walls and forming a carrier for said anvil die and providing for insertion and removal of said workpiece in said pair of dies from said front operating station, a wing extending across said base in a direction trans-

verse to said walls, a bending die carried by said wing and extending across said base in a direction transverse to said walls and being mounted on said wing for translatory movement relative thereto, pivot means mounting said wing on said frame for upward swinging movement for causing rocking of said bending die relative to said anvil die for bending said workpiece around the latter, a first upright power cylinder means mounted on said upright portion and operably connected with said slide to actuate the same for causing opening and closing movements of said anvil die, a second upright power cylinder means mounted on said upright portion and operably connected with said wing for actuating the wing and said bending die, a pair of front and rear racks mounted on said base and extending longitudinally thereof adjacent said front and rear ways, a shaft rotatably mounted in said frame and extending in a direction transverse to said walls, gear means connected with shaft and engaging said racks for causing movement of said frame along said ways in response to rotation of said shaft, and shaft rotating means manually accessible to said front operating station.
